UNITED STATES PATENT OFFICE.

EUGENE KOSTER, OF YONKERS, NEW YORK.

VAPORIZER FOR INTERNAL-COMBUSTION ENGINES.

1,095,645.

Specification of Letters Patent.

Patented May 5, 1914.

Application filed January 14, 1914. Serial No. 812,014.

To all whom it may concern:

Be it known that I, EUGENE KOSTER, a citizen of the United States of America, and a resident of Yonkers, county of Westchester, and State of New York, have invented certain new and useful Improvements in Vaporizers for Internal-Combustion Engines, of which the following is a specification.

10 The object of this invention is to effect the vaporization of gasoline and other liquids particularly in connection with the spraying of the liquid into air for the purpose of forming an explosive mixture for internal combustion engines. This particular use, however, is not essential to the invention.

A further object is to provide a device of simple construction which is readily applicable to internal combustion engines as usually arranged and without alteration of the parts.

In the accompanying sheet of drawings which forms a part of this application Figure 1 is a plan view of a gasket carrying the vaporizing device constructed in accordance with my invention. Fig. 2 is a section through the device. Fig. 3 is an elevation showing the device in connection with a carbureter and manifold.

A carbureter 1 of any desired type effects 30 the spraying of the oil into the air. The carbureter is joined to a manifold 2 by which the mixture is conducted to the engine. A gasket 3 of insulating material as fiber, felt or asbestos is inserted in the joint and carries 35 a resistance wire disposed in coils 4 4 which are suspended from hooks 5 5 embedded in the gasket and projecting into the gasket opening. A thin conducting strip 6 leads through the gasket into the opening 40 and is soldered to one end of the resistance wire. The other end of the strip is formed as one terminal of the vaporizer to receive a battery or magneto wire. The other end of the resistance wire is soldered to a conducting strip 7 which forms the other terminal. This need not be passed through the

insulating material of the gasket for direct connection with a battery wire, and as shown is laid on one side of the insulating material and soldered to one of two lining plates 8 8 50 and thus grounded on the machine through which the electric circuit is most conveniently completed. The lining plates are thin brass sheets which under pressure through the yielding resistance material of the gasket readily conform to the flange surfaces of the manifold and carbureter castings and permit a tight joint.

The oil enters through a pipe 9 to a float chamber 10 and thence through any suitable atomizer spraying or carbureting device to the carbureter chamber. From this chamber it is drawn together with the air entering through the openings 11 and 12 through the gasket and past the resistance coils and 65 through the manifold to the engine. The resistance wires are maintained at a low red heat by the passage of current, so as to sufficiently heat for the purpose of vaporization any unvaporized drops which are carried 70 by the current of air past the redhot coils. Such heat while sufficient to vaporize the oil is not sufficient to explode or ignite it. It will be seen that the device may be used in any conduit by itself for effecting the vaporization or in conjunction with an atomizer, or other form of carbureter, the action of which is imperfect, made to supplement and complete the vaporization.

What I claim, and desire to secure by Letters Patent of the United States, is—

A gasket consisting of an insulating portion with a facing of soft metal in combination with an electric resistance wire having a terminal connected to the metal facing of the 85 gasket, substantially as described.

Signed at New York, N. Y., this 12th day of January 1914.

EUGENE KOSTER.
